UNITED STATES PATENT OFFICE.

JOHN A. YEATMAN, OF OAKLAND, CALIFORNIA, ASSIGNOR TO UNITED IRON WORKS,
OF OAKLAND, CALIFORNIA, A CORPORATION OF CALIFORNIA.

CENTRIFUGAL PUMP.

1,023,776.

Specification of Letters Patent. Patented Apr. 16, 1912.

Application filed December 7, 1911. Serial No. 664,439.

To all whom it may concern:

Be it known that I, JOHN A. YEATMAN, a citizen of the United States, and a resident of the city of Oakland, county of Alameda, 5 and State of California, have invented certain new and useful Improvements in Centrifugal Pumps, of which the following is a specification.

The invention relates to centrifugal pumps. 10 and especially to means for counterbalancing the end-thrust of such pumps.

The object of the invention is to provide an automatic hydraulic end-thrust counterbalance for centrifugal pumps.

15 Another object of the invention is to provide an automatic hydraulic end-thrust counterbalance in which the pressure in the counterbalance chamber may be controlled and adjusted.

20 A further object of the invention is to provide an improved construction of the pump casing in which the part subjected to wear is formed separate and may be removed and replaced by a new part when 25 worn.

It is well understood by those familiar with centrifugal pumps that the discharge pressure between the runner and the case is never equal to the total discharge pressure 30 in the involute chamber or the discharge pipe and that these variations will cause an unequal pressure on the opposite sides of the runner, which has a tendency to move it out of central alignment. This 35 variation and end thrust also occurs either from the weight of the shafting and runner when operating vertically or from the action of the propelling mechanism or the unequal pressure caused by variations of the suction 40 and variations in the discharge pressure.

Heretofore, in the construction of centrifugal pumps provided with end-thrust counterbalancing means, the pressure or counterbalance chamber has received water 45 under pressure from the pump discharge or that part of the pump where the pressure is greater than the atmosphere, and has exhausted into the runner or the suction inlet in which the pressure is considerably 50 lower than that of the atmosphere. There has therefore always been a suction exerted on said chamber, which withdrew the water therefrom, and consequently reduced the pressure within the counterbalance chamber. The pressure exerted on

the water tending to force it out of the pressure chamber was the pressure of the water in the chamber plus the vacuum pressure in the runner or suction inlet. It is evident that if this suction effect could be eliminated, 60 a greater pressure per square inch could be obtained within the pressure chamber and hence a smaller chamber would be necessary to counter-balance the thrust and a more efficient pump would be obtained, since the 65 amount of water necessary to operate the counter-balance would be greatly lessened. In the present construction, I obviate these objectionable features of the prior art by arranging the counter-balance chamber in 70 communication with the usual source of pressure and with the atmosphere, thereby obviating the effects of the suction or vacuum.

The invention possesses other advantages 75 features, which, with the foregoing, will be set forth at length in the following description, where I shall outline in full that form of the invention which I have selected for illustration in the drawings accompanying and forming part of the present specification. The novelty of the invention will be included in the claims succeeding said description. From this it will be apparent that I do not restrict myself 85 to the showing made by such drawings and descriptions as I may adopt many variations within the scope of my invention as expressed in said claims.

Referring to the drawings:—Figure 1 is 90 a vertical section of a vertical shaft centrifugal pump showing the counter-balance chamber of my invention. Fig. 2 is a fragmentary section of the lower part of the pump showing a modification, of the means 95 for adjusting the position of equilibrium of the runner relative to the case.

My invention is particularly adapted to be used in connection with vertical shaft centrifugal pumps and I have illustrated in 100 the drawings a single stage or simple vertical shaft pump, but it is to be understood that the invention is equally applicable to multi-stage or compound pumps.

The pump consists of a case 2 having the usual involute chamber 3, suction inlets 4 and discharge outlet 5. Within the case 2 and attached to the vertical drive shaft 6 is a runner or impeller 7 arranged so that it lies substantially central of the case when 110

the pump is in operation. A collar 8, secured to the shaft 6 supports the shaft and runner when the pump is not in operation and is so placed that it is lifted out of contact with the upper part of the pump framing 9, when the pump is in operation.

The runner 7 is provided on opposite sides with the flanges 12-13 which form running joints to hold the impeller alined. 10 The flange 12 on the upper sides of the runner forms a running joint with the case 2 and the flange 13 on the lower side forms a running joint with an annular ring 14 secured to the case. This annular ring is 15 preferably formed separable from the pump casing so that it may be readily removed when worn and a new ring inserted in its place. This arrangement obviates the necessity of replacing the entire lower plate 20 15 of the case when the joint becomes excessively worn, a feature which is of material importance in pump operation.

Closing the lower end of the runner is a plate 16 either formed integrally with the 25 flange 13 or formed separately and securely attached to the flange, so that it moves vertically in unison with the runner. The flange 13, the ring 14 and the lower part of the case are so formed that a chamber 17 is 30 formed between the plate 16 and the lower plate 18 of the casing. This plate 18 is formed with an aperture therein, which acts as an outlet for the water in the chamber 17. This outlet is preferably formed of a 35 hollow plug or nipple 19, screw-threaded into the plate 18, so that its position may be adjusted vertically, and provided with a lock-nut 21 so that it may be fixed in adjusted positions. Formed centrally on the 40 lower side of the plate 16 is a cylindrical boss or piston 22 which fits into the nipple 19 and is movable vertically with respect thereto. This vertical movement of the piston 22 controls the outlet to the chamber 17.

45 In Fig. 2 I have shown a slight modification in which the nipple 19 projects upward in the chamber 17 and is provided with one or more holes 23 which are covered and uncovered by the vertical movement of the 50 piston. In this construction the piston is seated in the nipple at all times and is not withdrawn therefrom as it moves upward.

Water under pressure is applied to the 55 chamber 17 from within the case through the running joint between the ring 14 and the flange 13 and the area of the chamber is such that the pressure is sufficient to support the runner and its driving means. Whenever the pressure in chamber 17 exceeds the pressure on the opposite side of the runner, the latter will move with the shaft a short distance vertically withdrawing the piston 22 from the nipple 19, or uncovering the holes therein, depending 65 upon the construction used and allowing the

water in the chamber to discharge through the nipple and consequently reducing the pressure.

The circumferential length of the running joint between the ring 14 and the flange 13 being much greater than the length of the joint between the piston 22 and the nipple 19, the water is enabled to enter the chamber faster than it may discharge when the piston engages the nipple, consequently pressure is produced in the chamber 17. As the piston is moved out of the nipple, however, the water is discharged from the chamber with greater rapidity and the pressure therein is reduced. This operation is carried on automatically with the result of holding the runner in perfect balance. This arrangement also produces a downward path for the water so that sand does not become lodged in the chamber 17 and interfere with the operation of the balance. Under some circumstances, however, a variation in hydraulic pressure and of driving force, it has been found desirable to change the point of equilibrium of the runner relative to the case. This is accomplished by simply adjusting the position of the nipple 19.

A pipe or conductor 24 attached to the nipple 19 extends into the water of the well, or other water supply so that when the pump is being primed and started, air will not be drawn into the casing and prevent priming.

I claim:

1. In a centrifugal pump, the combination of a case, a runner mounted upon a shaft and revoluble within the case, a suction inlet passage, a closed end cylindrical portion extending from the runner on the side opposite the suction inlet, a cylindrical chamber in the case into which said cylindrical portion extends and is revoluble, a central outlet passage through the case opening into said chamber and a central piston on said cylindrical portion for controlling said passage. 100

2. In a centrifugal pump, the combination of a case, a runner mounted upon a shaft and revoluble within the case, a suction inlet passage, a flange projecting from the runner on the side opposite the suction inlet, said flange being closed on the end, a chamber within the case into which said flange extends and is revoluble, an outlet passage through the case opening into said chamber, a hollow plug adjustably secured in said passage, and a piston attached to the runner controlling the outlet through said plug. 115

3. In a centrifugal pump, the combination of a case, an inclosed runner mounted upon a shaft and revoluble within the case, a suction inlet passage concentric with the shaft upon one side of the case, an annular flange projecting from the runner into said. 125 130

inlet forming a running joint therein, a corresponding flange projecting from the opposite side of the runner, a chamber within the case into which said flange extends 5 and is revoluble, said case being provided with a passage opening into said chamber, and a piston attached to the runner for controlling said passage.

4. In a centrifugal pump, the combination of a case, a runner mounted upon a shaft and revoluble within the case, a suction inlet passage, a flange projecting from the runner on the side opposite the suction inlet, a plate closing the end of said flange, 15 a cylindrical chamber into which said flange of the runner extends and is revoluble, said case being provided with a passage opening into said chamber, and a piston attached to said plate controlling said passage.

20 5. In a centrifugal pump, the combination of a case, a runner mounted upon a shaft and revoluble within the case, a suction inlet passage, a closed end cylindrical portion extending from the runner on the 25 side opposite the suction inlet, a cylindrical chamber in the case into which said cylindrical portion extends and is revoluble, a hollow plug in said case forming an outlet to said chamber, said nipple being provided 30 with a laterally extending aperture, and means attached to said cylindrical portion, engaging said plug for controlling the outlet through said aperture.

6. In a vertical shaft centrifugal pump, 35 the combination of a case, a runner mounted on a shaft and revoluble within said case, a closed cylindrical portion extending downward from the lower side of the runner, a chamber in said case into which said 40 cylindrical portion extends and is revoluble, said case being provided with a downwardly projecting passage, aligned with the shaft, opening into chamber, and means on the lower side of said cylindrical portion 45 for controlling said passage.

7. In a centrifugal pump, the combina-

tion of a case, a runner mounted upon a shaft and revoluble within said case, an annular space between the runner and the end of the casing adjacent the discharge passage, the latter and said chamber being in constant communication, a hollow plug in the end of the casing forming an outlet passage to said chamber, said plug being movable relative to the end of the runner 50 so that the outlet passage may be controlled to vary the point of equilibrium of the runner.

8. The combination in a centrifugal pump of an automatic balancing device consisting of annular flanges projecting from the opposite sides of the runner, one of said flanges forming a running joint within the suction passage and the other extending into and forming a similar joint in a chamber formed on the opposite side of the case, an inlet passage connecting the interior of the pump chamber with said chamber, an outlet through said chamber, and a piston movable with said runner to control said 60 outlet.

9. In a centrifugal pump, the combination of a case, a runner mounted upon a shaft and revoluble within the case, a suction inlet passage, a closed end cylindrical 75 portion extending from the runner on the side opposite the suction inlet, a cylindrical chamber in the case into which said cylindrical portion extends and is revoluble, a central outlet passage through the case 80 opening into said chamber, a central piston on said cylindrical portion for controlling said passage and a conductor connecting said passage with a water supply.

In testimony whereof, I have hereunto 85 set my hand at San Francisco, California, this 1st day of December 1911.

inlet forming a running joint therein, a corresponding flange projecting from the opposite side of the runner, a chamber within the case into which said flange extends 5 and is revoluble, said case being provided with a passage opening into said chamber, and a piston attached to the runner for controlling said passage.

4. In a centrifugal pump, the combination of a case, a runner mounted upon a shaft and revoluble within the case, a suction inlet passage, a flange projecting from the runner on the side opposite the suction inlet, a plate closing the end of said flange, 10 a cylindrical chamber into which said flange of the runner extends and is revoluble, said case being provided with a passage opening into said chamber, and a piston attached to said plate controlling said passage.

20 5. In a centrifugal pump, the combination of a case, a runner mounted upon a shaft and revoluble within the case, a suction inlet passage, a closed end cylindrical portion extending from the runner on the 25 side opposite the suction inlet, a cylindrical chamber in the case into which said cylindrical portion extends and is revoluble, a hollow plug in said case forming an outlet to said chamber, said nipple being provided 30 with a laterally extending aperture, and means attached to said cylindrical portion, engaging said plug for controlling the outlet through said aperture.

6. In a vertical shaft centrifugal pump, 35 the combination of a case, a runner mounted on a shaft and revoluble within said case, a closed cylindrical portion extending downward from the lower side of the runner, a chamber in said case into which said 40 cylindrical portion extends and is revoluble, said case being provided with a downwardly projecting passage, aligned with the shaft, opening into chamber, and means on the lower side of said cylindrical portion 45 for controlling said passage.

7. In a centrifugal pump, the combina-

tion of a case, a runner mounted upon a shaft and revoluble within said case, an annular space between the runner and the end of the casing adjacent the discharge passage, the latter and said chamber being in constant communication, a hollow plug in the end of the casing forming an outlet passage to said chamber, said plug being movable relative to the end of the runner 50 so that the outlet passage may be controlled to vary the point of equilibrium of the runner.

8. The combination in a centrifugal pump of an automatic balancing device consisting of annular flanges projecting from the opposite sides of the runner, one of said flanges forming a running joint within the suction passage and the other extending into and forming a similar joint in a chamber formed on the opposite side of the case, an inlet passage connecting the interior of the pump chamber with said chamber, an outlet through said chamber, and a piston movable with said runner to control said 60 outlet.

9. In a centrifugal pump, the combination of a case, a runner mounted upon a shaft and revoluble within the case, a suction inlet passage, a closed end cylindrical 75 portion extending from the runner on the side opposite the suction inlet, a cylindrical chamber in the case into which said cylindrical portion extends and is revoluble, a central outlet passage through the case 80 opening into said chamber, a central piston on said cylindrical portion for controlling said passage and a conductor connecting said passage with a water supply.

In testimony whereof, I have hereunto 85 set my hand at San Francisco, California, this 1st day of December 1911.
